UNITED STATES PATENT OFFICE.

LEIGH W. HOSTETTLER, OF TARENTUM, PENNSYLVANIA, ASSIGNOR TO ALLEGHENY STEEL COMPANY, OF BRACKENRIDGE, PENNSYLVANIA, A CORPORATION OF PENNSYLVANIA.

JOURNAL-BOX LID.

Application filed November 23, 1923. Serial No. 676,560.

This invention relates to journal box lids and closing means therefor.

An object of this invention is to provide a closing means for journal box lids, where-
5 by the lid when in closed position is caused to bear on the top as well as the bottom of the box face.

A further object is to provide a closing means for journal box lids whereby the jour-
10 nal box may be effectually closed by the lid even though large clearances exist between the lid scrolls and the hinge pin or between the hinge pin and the box lug pin hole.

A still further object is to provide a jour-
15 nal box lid of the above type which is par-
ticularly adapted for use on a standard A.
R. A. (American Railway Association)
journal box.

These and other objects which will be
20 apparent to those skilled in the art, I ac-
complish by means of my invention, one
embodiment of which is shown, by way of
example, in the accompanying drawing in
which Figure 1 is a front elevation of a jour-
25 nal box lid embodying a form of this in-
vention and Fig. 2 is a central cross section
of the structure shown in Fig. 1.

Although it will be obvious that this in-
vention is applicable to journal box lids
30 generally I have shown the illustrated em-
bodiment of my invention as applied to a
standard A. R. A. journal box 1 which is
provided on the top with a conventional,
central hinge pin lug 2 having the usual
35 angularly disposed bearing faces 3 and 4.
A lid 5 is hinged to the box lug by means
of scrolls 6 formed on the lid which em-
brace the outer ends of a hinge pin 7 ex-
tending through a hinge pin hole 7' in the
40 box lug. The scrolls are preferably pro-
vided with hinge pin retaining ears 8, as
shown in Patent Number 1,425,092, issued to
me on August 8, 1922.

The lid is provided with a depending
45 guard flange 9 and with a projecting lip 10
by means of which it may be lifted to open
position.

The lid closing device includes a bar 11,
preferably of channel shape, and provided
50 with a supporting boss 12. A bar support-
ing stirrup 13 engages the boss 12 and holds
the bar in operative position. The stirrup
13 is supported from the hinge pin by strap
members 14 which are pierced to receive the

hinge pin. The stirrup or bar support is 55
independent of the lid and capable of
relative movement thereto about the hinge
pin.

The upper end of the bar 11 has a slot
15 in which is rotatably mounted a roller 60
16 adapted to cooperate with the angular
bearing faces 3 and 4 of the box lug. The
other end of the bar 11 extends downwardly
adjacent the box lid to which it is loosely
65 connected by means of a bolt 17 secured to
the box lid and extending through a slot
18 in the bar 11. A coil spring 19 surrounds
the bolt between the bar 11 and the box lid
and tends to force these two members apart.
A nut 20 is threaded on to the bolt 17 and is 70
adapted to vary the tension of the spring
19.

The lid closing bar 11 is adapted to ful-
crum on the supporting stirrup 13 and the
coil spring 19 maintains the roller 16 in con-
75 tact with one or the other of the bearing
faces on the box lug and also causes the
lid to bear on the top as well as the bottom
of the journal box when the lid is in closed
position. The extent to which the spring
80 75
19 separates the bar 11 and the lid 5 is deter-
mined by the position of the nut 20 on the
bolt 17. In opening the lid the roller 16
rides upward on the bearing face 4 of the
box lug and on to the bearing face 3, during
85
which movement the bar 11 fulcrums in the
stirrup 13 against the tension of the spring
19. The lid is held closed by the pressure
of the bar 11 on the spring 19 caused by
the roller forcing the upper end of the bar
90 85
outwardly.

Relatively large clearances between the
hinge pin and the hole in the lug are not
only permissible but are desirable. Rela-
tively large clearances are also provided
95 between the hinge pin and the lid scrolls,
as illustrated in Fig. 2.

Having thus described my invention what
I claim as new and desire to secure by
Letters Patent is:

1. The combination with a journal box
having a hinge-pin lug provided with
angularly disposed bearing faces, of a hinge
pin extending through said lug, a lid hinged
on said pin, a rigid member adapted to press
100
said lid closed, at one end cooperating with
said bearing faces and at the other end
yieldingly associated with said lid and a

support for said member mounted on said pin.

2. The combination with a journal box having a hinge-pin lug provided with angularly disposed bearing faces of a hinge pin extending through said lug, a lid mounted on said pin, a bar adapted to press said lid closed, at one end cooperating with said bearing faces and at the other end loosely bolted to said lid, a spring interposed between said bar and lid, means for limiting the expansion of said spring and a support for said bar mounted on said pin.

3. The combination with a journal box having a hinge-pin lug provided with angularly disposed bearing faces of a hinge pin extending through said lug, a lid mounted on said pin, a bar adapted to press said lid closed, at one end cooperating with said bearing faces and at the other end loosely bolted to said lid, a spring interposed between said bar and lid, means for limiting the expansion of said spring and a support for said bar mounted on said pin.

larly disposed bearing faces of a hinge pin extending through said lug, a bar adapted to press said lid closed and provided with a supporting boss, said bar at one end having a roller mounted to cooperate with said bearing faces and at its other end provided with a slot and bolt connection to said lid, a spring interposed between said bar and lid, and a supporting stirrup for said bar mounted on said hinge pin and engaging 25 said supporting boss.

In testimony whereof, I have hereunto subscribed my name this 20th day of November, 1923.

LEIGH W. HOSTETTLER.
